UNITED STATES PATENT OFFICE

GEORGE E. WEBB, OF MILWAUKEE, WISCONSIN, ASSIGNOR TO KOEHRING COMPANY,
OF MILWAUKEE, WISCONSIN, A CORPORATION

BOOM-BUCKET-CONTROL MECHANISM FOR CONCRETE-DISTRIBUTING APPARATUS

Application filed June 15, 1927. Serial No. 199,042.

The present invention appertains to the art of concrete distributing apparatus or pavers of the well known Koehring boom and bucket type, and relates particularly to improvements in bucket control mechanisms therefor.

The mechanisms hereinafter depicted represent radical departures from the customary instrumentalities by which the distributing bucket is moved to and fro along the boom of the paver and the door thereof is actuated in its opening and closing movements. Whereas these mechanisms heretofore have embodied a complication of clutch devices, cable operating means, knock-out and trip instrumentalities, etc., the present improvements are characterized by a markedly simplified arrangement of devices with accompanying facility of manipulation and control.

In carrying out the invention, instead of the usual intermittently operated or reversing cable control, there is here provided a continuously moving endless cable actuator with which a cable grip mechanism cooperates to effect traverse of the bucket along the boom in opposite directions.

The mechanism also embodies a novel type of door operating mechanism coacting in a peculiar manner with the boom to produce the positive opening and closing movements of said door incident to travel of the bucket along the boom.

For a full understanding of the invention, reference is to be had to the accompanying drawings wherein:

Figure 1 is a side elevation of the boom and bucket mechanism forming the subject matter of this invention;

Figure 2 is an enlarged view of the bucket and the door operating mechanisms therefor, the door of the bucket being shown in its open position and as it is about to be tripped for closing, just prior to return to the charging position at the inner end of the boom;

Figure 3 is a transverse sectional view through the boom on the line 3-3 of Figure 2, a portion of the trolley support being broken away to show the cable grip mechanism and associated parts in elevation;

Figure 4 is a detail view of the trip arm carried by the boom by which the door actuating instrumentalities are rendered operative to produce closing movement of the door;

Figure 5 is a detail view of a supporting member for yieldingly holding the rotatable friction wheel used in this mechanism in co-operative relation to the boom;

Figure 6 is a longitudinal section of the inner end of the boom, showing more clearly the details of the manipulative control means which causes the operation of the cable grip mechanism;

Figure 7 is a detail perspective view of the rotatable friction wheel used in conjunction with the door operating mechanism, together with its trip pawl and associated trip lever;

Figure 8 is a fragmentary sectional view of the outer end of the boom showing the point cable sheave and the outer cam shaft bearing;

Figure 9 is an enlarged view of the parts of the bucket door operating mechanism, including the friction wheel actuator which is disposed in the position assumed at the commencement of the closing movement of the door;

Figure 10 is a similar view, showing the position taken when the door is fully closed and the bucket returned to its innermost limit of movement on the boom;

Figure 11 is a detail view of the cable grip cam;

Figure 12 is a detail view of one of the cable grip levers;

Figure 13 is a detail view showing one of the cable clamps; and

Figure 14 is a detail view of one of the complementary sections of a cable clamp.

Like reference numerals designate corresponding parts throughout the several figures of the drawing.

Referring to the drawings, A designates the frame of the paver apparatus, B a portion of the mixing drum, and C the discharge chute therefor. The boom D which is of the conventional form and provided with vertical adjusting means as well as means for

swinging it horizontally, is connected by the vertical pivot E to the bracket F attached to the mixer frame A. This boom, as shown in Figure 3, comprises the spaced channel members G—G on the lower flanges of which the trolley wheels H operate. From the trolley I is swung the distributing bucket J, the hollow head casting K of which is mounted upon the longitudinal pivot L.

- 10 At this point it is believed desirable to describe the main feature of these improvements, namely the bucket operating mechanism by means of which the bucket J is caused to traverse the boom. Power for this purpose is taken preferably from the drum ring gear B' with which a pinion 1 meshes. Through this pinion, motion is transmitted to the shaft 2 and drive gear 4 mounted on the stub shaft 5. Upon one side of this drive gear is formed 20 a grooved pulley 6 about which passes the endless cable 7 which is trained around the spaced guide sheaves 8 carried by the inner end of the boom, the two horizontally disposed reaches of the cable extending along beneath 25 the boom to the point sheave 9. This cable has imparted to it the continuous motion of the drum, though it is to be understood that such corresponding continuous motion might readily be taken direct or otherwise indirectly from the prime mover and therefore I 30 do not wish to be limited in this regard.

Motion from this cable is transmitted to the bucket at will through certain cable grip mechanism now to be set forth. Mounted to 35 extend the full operative length of the boom and between its channel members is a square shaft 10. Figures 6 and 8 show the outer end of the shaft to be disposed in a rotatable bushing 11 mounted in the bracket 12 which 40 connects the outer ends of the boom channel members together and its inner end is similarly mounted in the bushing 11' carried by the inner bracket 12'. At this end the shaft carries a bevel pinion 13 which meshes with 45 a corresponding pinion 14 on the end of the vertical shaft 15, which in turn carries an operating member 16, in this form a sprocket wheel which is designed to be operated by any manipulative means (not shown) to impart a 50 rocking motion to the control shaft 10. It will be observed that the shaft 15 is disposed in vertical alignment with the boom pivot E so that turning movement of the boom would transmit motion to the sprocket chain which 55 would lead from the sprocket 16 to a corresponding sprocket, for example on the operator's platform, but rocking motion of the shaft would only be obtained by a relative movement of the shaft 15 under the control 60 of manipulative means at the command of the operator.

Rocking of the shaft 10 operates a cam 17, a detail of which is illustrated in Figure 11. This cam is provided with opposing trunnions 18 and is broached to slidingly receive

the shaft 10. It is mounted between the spaced uprights 19 forming part of the connecting web between the two side members 20 of the trolley I, one of the trunnions 18 being grooved at 18' to receive a retaining screw 18''. 70 Thus in the movement of the trolley and its bucket, this cam slides along the shaft and is always in position to cooperate with the adjacent finger levers 21, one at each side of the cam, pivoted at 22 on the web. Each of 75 these fingers coacts with a grip member or block seated in a recess in the web portion of the trolley and specifically shown in Figures 13 and 14 to comprise complementary interengaging sections 23—23', formed to embrace 80 the cable 7 passing therethrough. Since one of these blocks embraces the outgoing reach of the cable and the other the incoming reach, it is readily understood that by a grip action 85 of one or the other, the cable movement will shift the bucket in one direction or the other along the boom as the cam 17 is turned by the shaft 10 to actuate the respective finger levers 21. The movement of the bucket may be discontinued at any time in its travel by simply 90 restoring the controlling cam to its normal upright position shown clearly in Figure 3.

Passing now to the bucket door operating mechanism, and referring to Figures 1 and 2, the bucket J is provided with a swing door 24 suspended by the two arms 25—26 and weighted at its upper edge at 27 to counterbalance. The rear edge of the bucket opening, as shown in Figure 2, has secured thereto a flexible scraper 28 which removes any material tending to adhere to the surface of the door as it swings into open position and insures tight closure when the door swings back to closed position. To the arm 25 is connected the actuating rod 29 having at its connecting 105 end the cushioning spring 30 within a casing 30'. This forms an adjustable connection with the arm for insuring a proper closing of the door over the bucket opening.

The rod 29 is connected at its other end 110 with a crank arm 31 on the end of the shaft 32 journaled in the bearing 33 on the forward wall of the bucket. The crank arm 34 extending from the central portion of the shaft 32 is connected by the vertically disposed rod 115 35 with a crank arm 36 carried by the short shaft 37 journaled in the outer end of a supporting lever 38, which in turn is pivoted at 39 in the hollow head casting K of the bucket. With the inner end of the lever 38, a spring 40 coacts and tends to yieldably hold the shaft 37 at its elevated position, this position being 120 adjustably determined by an adjustable stop screw 41.

Upon the shaft 37 is fixedly mounted the 125 friction wheel 42, the peripheral portion of which is formed with interruptions or opposing flat portions 42^a and 42^b. The periphery of the wheel is provided with suitable friction material. Interlocked with the shaft and 130

the wheel is a trip lever 43 extending in opposed relation to the crank arm 36. It is the function of this friction wheel to operate in contact with the under surface of the adjacent boom channel member as the bucket J travels along the boom and by its rotative movement to shift the bucket door 24, as will now be more clearly set forth.

Assume that the distributing bucket has deposited its contents upon the surface and under power of the actuating cable 7 is returning towards the inner end of the boom for another charge of materials. Referring to Figure 2 of the drawings, the trip lever 43 is in its upper vertical position, and in its path of movement a trip arm 44 secured to the boom, depends. It is to be noted that the flat portion 42^a is uppermost and slightly spaced from the boom so that the wheel 42 is out of contact and stationary. Immediately the trip lever 43 impinges the arm 44, the shaft 37 is turned in its bearing, causing the true periphery of the wheel 42 to contact with the superposed boom flange, as shown distinctly in Figure 9, marking the commencement of the closing movement of the bucket door, the rotary motion of the wheel being transmitted through the parts 36, 35, 34, 32, 31 and 29 to the door lever 25.

When the flat portion 42^b is reached, as shown in Figure 10, rotation of the wheel is discontinued and the door has reached its closed position. The movement aforesaid brought a oneway acting pawl 45 carried by the wheel 42 into cooperative relation with the boom with which it has biting engagement. The bucket is now charged with another load of material and then by means of the cable grip mechanism hereinbefore described it is moved outwardly along the boom until the desired point is reached, whereupon the operator reverses the cable grip so as to be effective upon the incoming reach of the cable. In the outward movement the pawl 45 simply slides along the surface of the boom without any operative effect, but upon reverse of the travel the biting engagement mentioned shifts the wheel 42 sufficiently to bring the true periphery at its opposite side from that referred to above into contact with the boom and the continuation of this inward travel moves the bucket door into open position such as shown in Figure 2, dropping the contents on the surface below. The closing movement of the bucket door is then effected by contact of the trip lever 43, now again in its elevated position, in the manner previously set forth.

Further details of construction may now be mentioned. Pivottally mounted upon the bucket head K adjacent the wheel 42 is a safety friction stop 46 which permits free movement of the wheel 42 in one direction but prevents any reverse of such movement which might possibly allow the wheel 42 to acci-

dentially operate reversely to the desired direction as will be clearly understood.

In order to control the distribution of the contents of the bucket, I have provided for a variable opening of the bucket door. To this end the crank 31 and its connection with the rod 29 are formed with a series of apertures 31'. The number provided in the illustrated construction will permit of three different degrees of opening of the door such as shown in the full and dotted positions of Figure 2 of the drawings.

The door 24 has a movement in the plane of its body, or that of the opening of the bucket which it closes. Also as it floats, so to speak, to and from closing positions there is caused slight movement lateral to such plane. This ensures tight closing especially and the latter movement is obtained by the linkage mounting of the door and the greater length of the arm or link 26 as compared with that of the arm or link 25.

Having thus described my invention, what I claim as new and desire to secure by Letters Patent is:—

1. In combination, a boom, a bucket reciprocally traversing said boom, and means to move said bucket relative to the boom comprising a continuously moving actuating member and a power means for driving the continuously actuated member.

2. In combination, a boom, a distributing element to traverse said boom, an actuator continuously moving along the boom, and control means for causing the distributing element to at will partake of the movement of the actuator.

3. In combination, a boom, a distributing bucket to traverse said boom, an operating cable, means for actuating said cable, and cable grip means for positively engaging the cable and transmitting its motion to the bucket.

4. In combination, a boom, a distributing bucket to traverse said boom, an operating cable endless in form and having its reaches extending outwardly and inwardly of the boom, means for actuating said cable, and cable grip means arranged to engage either of the reaches of the cable and to impart either outward or inward movement of the bucket relative to the boom.

5. In concrete distributing apparatus, a boom, a carriage movable along said boom, a distributing bucket supported by said carriage, an endless cable having its reaches extending along the boom in spaced relation, a cable grip mechanism carried by said carriage, and control means for causing engagement of said grip mechanism with one or the other of the cable reaches to thereby control the direction of movement of the bucket.

6. In concrete distributing apparatus, a boom, a carriage movable along said boom, a distributing bucket supported by said car-

riage, a cable mounted to have outward and inward movement relative to the boom, cable grip means on said carriage, and control means operable to effect engagement of the grip means with the cable to impart outward or inward movement to the bucket.

5 7. In concrete distributing apparatus, a mixing drum, a boom, a carriage to traverse said boom, a bucket supported by said carriage, an endless cable driven from said drum and extending along the boom, and cable grip means carried by the carriage and operable to effect reverse movements of the bucket from said cable.

10 8. In concrete distributing apparatus, a boom, a carriage movable along said boom, a distributing bucket supported by said carriage, a cable mounted to have outward and inward movement relative to the boom, cable grip means on said carriage, and control means operable to effect engagement of the grip means with the cable to impart outward or inward movement to the bucket, including an actuating cam and manual operating 20 means for shifting said cam to render the grip means operable on the cable.

25 9. In concrete distributing apparatus, a boom, a carriage movable along said boom, a distributing bucket supported by said carriage, an endless cable having its reaches extending along the boom in spaced relation, a cable grip mechanism carried by said carriage, including a grip member cooperative with each reach of the cable, and control 30 means disposed between said grip members and operable upon one or the other depending upon whether the bucket is to be moved inwardly or outwardly of the boom.

35 10. In concrete distributing apparatus, a boom, a carriage movable along said boom, a distributing bucket supported by said carriage, an endless cable having its reaches extending along the boom in spaced relation, a cable grip mechanism carried by said carriage 40 including a grip member cooperative with each reach of the cable, a rock shaft extending longitudinally of the boom, and a cam member slidably mounted on said shaft between the grip members and adapted to engage one or the other of the same when the 45 shaft is rocked to thereby render the bucket operable by the cable.

50 In testimony whereof I affix my signature.

GEORGE E. WEBB.
